UNITED STATES PATENT OFFICE

2,529,921

STAETER BOOSTER

Elton Davolt, Kelso, Wash.

Application May 6, 1946, Serial No. 667,518

6 Claims. (Cl. 123—179)

1

The principal object of my invention is to eliminate the difficulty in starting a motor car engine or any spark fired engine due to a weak spark at the plugs, especially when the motor is cold and stiff, as in cold weather, when a heavy load is drained from the battery by the starter.

One of the objects of this invention is to provide an inexpensive compact form of starter booster which may be readily installed upon any type of automobile.

Another object of this invention is to provide a starter booster which is inexpensive to manufacture, efficient in operation, and easily installed without material change of any of the motor parts of the ignition, starter and battery system of an ordinary automobile.

Another object of this invention is to provide an auxiliary starter booster which will step up the spark energy upon starting a car and thereby overcome the additional load required for starting when the motor is cold and add to the efficiency of a weak battery.

Another object of this invention is to provide a starter booster adapted to improve the efficiency of the starting equipment without the necessity of an auxiliary battery.

One of the novel features of this ignition booster system is the simplicity of its construction in having only two main mechanical parts.

I accomplish the objects of this invention in the manner set forth in the specification and accompanying drawing in which

Fig. 1 is a diagrammatic illustration of the circuit booster motor, generator and circuit connections as used in connection with my improved starter booster.

Fig. 2 is a diagrammatic illustration of a moisture proof receptacle adapted to contain the starter booster motor, generator and circuit connections, the outlets and terminals being designated by the numbers 1, 4, 5 and 9.

The wiring, circuit breaker switch and motor-generator set are all of a character which may be obtained on the market and the novelty of the invention lies in the proper adaptation of its parts to the unit for the purposes required and in the manner the units are connected with the ignition and starter circuits. The auxiliary motor-generator set 10—11 is of the single unit type. In an automobile using the six volt battery the motor 10 of the motor-generator set should be a six volt motor and the generator 11 of the booster set should be a three volt generator. Terminal 1 connects with the ignition switch 1a, terminal 4 connects with the spark coil primary 4a, terminal

2

5 connects with the starter switch 5a and terminal 9 connects with the ground of the ignition system.

When the ignition switch is closed and the motor-generator set is not in operation the current flows through terminal 1, conductor 2, circuit breaker 3, conductor 12 and output terminal 4, connecting with spark coil primary 4a.

When starter switch 5a is closed a sufficient portion of the current flows from the battery 10 through terminal 5 to conductor 6 to energize the motor 10 of the motor-generator set 10—11 and magnetic coil 7 thus breaking contacts 14 and 15 of the circuit breaker 3.

With the circuit breaker open and motor-generator set 10—11 in operation the current from the battery which is not used to energize motor 10 of the motor-generator set 10—11 flows through conductor 2 to the negative pole, or terminal, of the generator 11 of the auxiliary motor-generator set 10—11, unites with the current developed by the generator 11 of the booster-generator set 10—11 and passes out through the positive output terminal; and the combined current from the battery and from the generator 11 of the auxiliary motor-generator set 10—11 flows through the wire 2b, the conductor 12 and output terminal 4 to the spark coil primary 4a, then to the ground 9.

The starter booster system is enclosed in a moisture proof container 16 with four terminal connections as indicated by Fig. 2.

Terminal 1 connects with the regular ignition switch 1a. Terminal 4 connects with the spark coil primary 4a. Terminal 5 connects with the regulator starter switch 5a, and terminal 9 connects with the ground. By reversing the terminals on the motor-generator set 10—11 this unit may be used on any ignition system with polarity reversed from the system contemplated by the description in this specification.

The container 16 may be located at any place beneath the hood of an automobile, which is convenient for making the connections. The fire wall or dash panel just beneath the hood will usually be found to be such a location.

When the switch 5a is open, the breaker points 14 and 15 of circuit breaker 3 are closed by means of the normal position of the spring element 13; and all effect of the motor-generator set 10—11 will be eliminated. The starter motor of the automobile is connected by the wire 5b with the output terminal of the regular starter motor switch 5a. It is apparent that when thus connected magnetic coil 7 and the motor-generator set 10—11 will operate only during the period that

the starter motor switch is closed and that upon releasing the starter motor switch a direct circuit, eliminating the motor-generator unit, will then be re-established through circuit breaker 3, contact points 14 and 15, conductor 12 and terminal 4 to spark coil primary 4a.

Having described my improved starter booster system what I claim is:

1. In an engine starting system comprising a battery, a starter motor, a switch therefor and a spark coil primary circuit; an auxiliary motor-generator set; electric conducting means, connecting the starter motor switch with the auxiliary motor-generator set, adapted to establish activating means to the auxiliary motor-generator set by establishing electrical connection between said set and the battery during the period the starter switch is closed; electric conducting connection between the generator of the auxiliary motor-generator set and the spark coil primary circuit, adapted to cause current to flow from the auxiliary motor-generator to the spark coil primary circuit during the time the starter motor switch is closed.

2. In an engine starting system comprising a battery, a starter motor, a switch therefor and a spark coil primary circuit; a starting booster device, consisting of a motor-generator set, connected by an electric conductor with the starter motor circuit so as to be activated by closing the starter motor circuit by closing the starter motor switch and electric conducting means connecting the auxiliary motor-generator set with the ignition system current at the time of starting the starter motor.

3. In an engine starting system comprising a battery, a starter motor, a switch therefor and a spark coil primary circuit; an auxiliary motor-generator set; electric current flow connecting means between the battery and the motor of the auxiliary motor-generator set, said electric flow connecting means being adapted to establish a flow of current from the battery to the motor-generator set by closing of the starter motor switch; and, electric flow connecting means between the generator of the auxiliary motor-generator set and the spark coil primary circuit.

4. In an engine starting system comprising a battery, a starter motor, a switch therefor and a spark coil primary circuit; a starting booster device consisting of an electric motor-generator set, connected by electric conductor means with the starting motor circuit and with the ignition sys-

tem primary circuit current while the starter motor current switch is closed.

5. In an engine starting system comprising a battery, a starter motor, a switch therefor and a spark coil primary circuit; an auxiliary motor-generator set; electric flow connection means between the battery and the motor of the auxiliary motor-generator set, said connecting means being adapted to close the connecting means and establish a flow from the battery to the generator of the motor-generator set when the switch to the starter motor is closed, said means including an electric magnetic device, breaker points in the main ignition circuit adapted to being opened by activating the electromagnet device by closing the starter motor switch; and, electric current conducting means between the generator of the auxiliary motor-generator set and the spark coil primary circuit, adapted to supplement the spark coil primary circuit during the time the breaker points are open.

6. In an article of manufacture for convenience of handling in the automobile supply business; a starter booster comprising an auxiliary motor-generator set in a sealed container, adapted to being attached to the fire wall, engine or frame of the automobile, said motor-generator set being connected to electric conductors extending in the form of terminals beyond the sealed container adapted for connecting said terminals by electric conducting means to the starting motor switch, the main ignition circuit, the spark coil primary circuit and the ground, the starter switch connection being adapted to establish an activating current from the battery to the motor of the auxiliary motor-generator set, said device being adapted for use in connection with the starter system of an automobile having a battery, a starter motor, a switch therefor and a spark coil primary circuit.
